UNITED STATES PATENT OFFICE.

JOHN A. CALDER, OF TORRINGTON, CONNECTICUT, ASSIGNOR TO THE TORRINGTON COMPANY, OF TORRINGTON, CONNECTICUT, A CORPORATION OF CONNECTICUT.

WIRE FEEDING AND CUTTING MECHANISM FOR LATCH-NEEDLE-MAKING MACHINES.

Application filed July 30, 1921. Serial No. 488,599.

To all whom it may concern:

Be it known that I, JOHN A. CALDER, a citizen of the United States, residing at Torrington, in the county of Litchfield, 5 State of Connecticut, have invented certain new and useful Improvements in Wire Feeding and Cutting Mechanism for Latch-Needle-Making Machines, of which the following is a description, reference being had 10 to the accompanying drawing and to the figures of reference marked thereon.

This invention relates to new and useful 15 improvements in wire feeding and wire cutting mechanism for latch needle making machines.

The present invention has for its object 20 the improvement of certain features of the wire feeding and wire cutting mechanism disclosed in the pending application of John 25 A. Calder, Serial Number 309,579, filed July 9, 1919, and assigned to the Torrington Company, the assignee of the present invention.

In this prior application, the wire is 25 drawn from its source through suitable guiding and tensioning devices by two levers pivoted together intermediate their ends. These levers are forced together by a sliding wedge arranged to reciprocate between their 30 upper extremities so as to bring together the cutter bars mounted on the lower extremities of the levers. The operating mechanism for the sliding wedge for the lever is constructed and arranged to first give the cutter 35 bars on the levers a slight gripping action on the wire for the feeding stroke and thereafter the cutter bars are forced strongly together to sever the determined length of the wire.

40 One of the objects of the present invention resides in providing the pivoted levers which operate the feeding and cutting dies with adjustable shoes adapted to receive the wear and frictional contact of the sliding 45 operating wedge, whereby a more powerful cutting action is provided and undue wear eliminated.

Still another object of this invention resides in providing an improved adjustable 50 mounting for the wire guide post located immediately above the cutters and through which the wire is guided to the cutters.

Still another feature of this invention resides in providing improved means for ten-

sioning the wire and for guiding it to the 55 wire feeding and cutting dies.

Another feature of this invention resides in providing an improved mounting for the wire guide in order to adjust the line of wire feed relatively to the cutter edges so 60 that different portions of the cutting edges may be utilized to sever the wire.

These and other objects will be apparent from a perusal of the accompanying specification when taken in connection with the 65 drawings.

Referring now to the drawing:—

Figure 1 is a front view of the improved device;

Figures 2 and 3 are plan and side views of 70 the wire tensioning rolls;

Fig. 4 is a side view partly in section of the wire feeding and guiding mechanism, and

Fig. 5 is a detail in perspective of the 75 adjusting means for the wire guide post.

Referring now to the drawings, the wire W is led from a suitable supply to the wire cutting dies where a measured length of wire is served from the stock prior to its 80 being further formed. This feeding and cutting mechanism comprises a suitable frame or bracket 43 on which is mounted a sliding head 44. This head is raised and lowered by a lever 45 formed with a rounded 85 head 46 adapted to extend between lugs 47 and 48 carried by the head 44. Suitable mechanism is provided, although not shown, for operating the lever 45 at the proper time.

Mounted on the sliding head 44 are the 90 two cutting levers 52 and 53. These levers are pivoted to turn about a supporting pivot 54, threaded into the sliding head. Each lever carries a cutter 55 adjacent the lower 95 end thereof, and these cutters are used for not only severing the wire, but also for gripping it to feed it forwardly. The two levers 52 and 53 are pressed together at their upper ends by means of the spring 56 which accordingly operates to normally separate the cutters 55. The cutters are forced 100 positively toward each other by a sliding cam 57 formed with inclined faces 58 adapted to engage the wear shoes 58' and 58" carried by the ends of the adjusting screws 105 59, one of said screws being carried by each lever. These wear shoes constitute one of

the improved features of the present appli-

cation. Heretofore, the sliding block 58 has made direct contact with the inwardly projecting ends of the screws 59. In the present construction, by mounting these shoes directly on the adjusting screws, a much broader contacting face is provided and consequently a far greater forcing action on the cutting dies is obtained. So also, the life of the adjusting screws is preserved since with the old construction, the wearing action on the small ends of these screws was considerable.

The sliding cam 57 is mounted on the sliding head and is moved thereon by a rock lever suitably pivoted in a manner not clearly shown, to a bracket secured to the sliding head 44 so that the rock lever moves up and down with the sliding head.

The rock lever has a round headed arm 55 which extends into an opening 66 in the cam 57. The rock lever 60 is operated by means of a lever, not shown, which has a vertical extension 70 carrying an adjusting screw 71, the head of which is adapted to bear against the rock lever 60. A spring 72 connected at one end to the extension 70 and at the other end to the rock lever forces said lever against the head of said screw. Suitable means disclosed only in said prior application is provided for giving the extension 70 first a rapid movement followed by a substantial dwell and finally a quick movement to bring about the cutting of the wire.

The wire indicated at W in the drawings is led from any suitable source, first led preferably through the guide bush 72 which has a suitable bore corresponding to the diameter of the wire used. The bush is supported directly in the line of the wire feed by means of the bent supporting arm 73. By this means the wire is properly guided to the tensioning rolls.

The tensioning and guide rolls 74 and 75 which also form a feature of the invention, are mounted on the curved supporting arms 76 and 77. Arm 76 is fast to one side of the machine, while arm 77 is pivoted to the opposite side. The spring 78 provides the necessary tension to force the two rolls together. Roll 75 has a peripheral flange 50 working in a central peripheral groove in roll 74 so that the wire in passing between the flange and groove is properly held under proper tension as must be evident.

On emerging from the rolls, the wire is led through a suitable guiding opening in the cam 57 thence through the pivot bolt 54 and then past a guide post to the cutting and feeding dies 55.

This guide post, which likewise forms a feature of this application, is constructed and arranged so that the line of wire feed can be varied with relation to the edge of the cutting dies. By this construction, it is unnecessary to always use the same portions 65 of the cutting edges of the dies so that the

dies can be used for a considerable longer period of time than heretofore.

In its preferred form, this adjusting means comprises a supporting block 76 secured to the frame or bracket 43 by means of a screw 77 or the like. This block is provided with a recess 78 therethrough forming a guideway in which slides the tongue 79 of the post 80, formed with a forwardly projecting flange 81 suitably perforated as at 82 and with a vertical flange 83 suitably bored as at 84 and 85 to receive the fastening and adjusting screws 86 and 87 respectively. The fastening screw 86 threads into a registering bore 88 in the block 76 whereas the end of the adjusting screw 87 contacts against the face of the block. By this construction, the post can be readily adjusted in and out relatively to the supporting block so that the wire passing through the perforation 82 of the post will be correspondingly shifted forwardly and backwardly across the edges of the cutting dies 55 located immediately under the post.

It will be obvious that minor changes in the details of the construction and the arrangement of the parts may be made without departing from the spirit of the invention as set forth in the appended claims.

Having thus described the invention, what I claim as new and desire to secure by Letters-Patent, is:—

1. A wire feeding and cutting mechanism for a latch needle making machines comprising a frame, a slide reciprocable therein, cutter bars movably mounted on said slide and adapted to grip said wire to feed the same forwardly, and means for putting a tension on the wire comprising two opposed rolls arranged in the line of feed of the wire, and means for resiliently pressing said rolls together.

2. A wire feeding and cutting mechanism for a latch needle making machine comprising a frame, a slide reciprocable therein, cutter bars movably mounted on said slide and adapted to grip said wire to feed the same forwardly, two arms connected to said frame, and resiliently pressed together, a roller on the end of each arm, said rollers having interfitting flanges and grooves located in the line of wire feed whereby to hold said wire under tension.

3. In combination, a frame, a slide vertically reciprocable thereon, a pair of levers pivoted together and to said slide, a pair of wire gripping bars on the lower ends of said levers, a guide on said frame adapted to guide a wire transversely across the path of movement of said bars, means located above said levers for shifting the same about their pivots, a pair of arms resiliently pressed together on said frame and projecting inwardly above said levers, over the line of wire feed, each arm having a roller mounted

thereon, said rollers having interfitting flange and grooved portions adapted to receive and grip the wire therebetween to hold said wire under tension.

- 5 4. A wire feeding and cutting mechanism for a latch needle making machine comprising a frame, a slide vertically reciprocable thereon, a pair of spring pressed levers pivotally mounted intermediate their ends on 10 said slide and provided with wire gripping and cutting dies on their lower ends, a wedge fixed to said frame between the other ends of said levers for forcing said levers outwardly on movement of said slide toward said 15 wedge, a wear block mounted on each lever to engage said wedge, and means for adjusting said wear block.
5. In a wire feeding and cutting mechanism for a latch needle making machine, the 20 combination of a frame, opposed dies mounted thereon for movement toward and from each other for gripping and severing the wire, means for guiding the wire in a plane passing across the plane of movement of said 25 dies, said means being adjustable parallel to the cutting edges of said dies whereby to change the point along the cutting edges at which the dies bite into the wire.

6. In a wire feeding and cutting mechanism for a latch needle making machine, the 30 combination of a frame, a slide vertically reciprocable thereon, opposed wire dies mounted on said slide for movement toward and from each other for gripping the wire, means for guiding a wire substantially transversely 35 of the plane of such gripping movement, and means whereby said guiding means may be adjusted substantially parallel with the gripping edges of said dies.

7. In a wire feeding and cutting mechanism for a latch needle making machine, the combination of a frame, a slide vertically reciprocable thereon, opposed wire dies mounted on said slide for movement toward and from each other for gripping the wire, means 40 for guiding a wire transversely of the plane of such gripping movement, said means comprising a recessed block connected to said frame above said dies, a post having a tongue adjustably fitting within said recess, and a 45 flange provided with a guide bore for said wire, and means for adjusting said post on said block, whereby to alter the point of contact of said wire with respect to said dies.

In testimony whereof, I affix my signature.
JOHN A. CALDER.
